UNITED STATES PATENT OFFICE.

HARRY A. DALY, OF PHILADELPHIA, PENNSYLVANIA.

CONCRETE STEP.

Application filed June 14, 1923. Serial No. 645,247.

To all whom it may concern:

Be it known that I, HARRY A. DALY, a citizen of the United States, residing at Philadelphia, in the county of Philadelphia and State of Pennsylvania, have invented certain new and useful Improvements in Concrete Steps, of which the following is a specification.

My invention relates to concrete steps and more particularly to interlocking concrete steps adapted for use in stoops or stairways. The object is to provide steps made of concrete which are simple and durable in construction, easily and cheaply manufactured and easily assembled into a stoop or stairway.

This object, and other advantageous ends which will be described hereinafter, I attain in the following manner, reference being had to the accompanying drawings in which—

Figure 1 is a central section through a stoop constructed of my improved steps,

Figure 2 a perspective view of a step constructed in accordance with my invention,

Figure 3 a fragmentary perspective view of the landing step with the securing means,

Figure 4 a perspective view of a reinforcing cage constructed in accordance with my invention,

Figure 5 a longitudinal central section through Figure 4, and

Figure 6 a section on line 6—6 of Figure 5.

Referring to the drawings, 1 indicates a wall of a building, such as the wall under a doorway, having stoop walls 2 extending therefrom and disposed at the opposite sides of the stoop. My improved steps 3 are superposed and mounted on the walls 2. The steps are locked to each other by interlocking means which comprise a shoulder 4 in the upper meeting corner of one step for receiving the lower meeting corner of the

superposed step, and having vertically projecting interlocking bars 5 adapted to take into vertical holes 6 in the corner of the superposed step. The under side of each step is arched as shown at 7 to provide a light and rigid step. A reinforcing cage 8 is embedded in each step and has secured thereto the vertical projecting bars 5. The bars 5 are preferably bent at right angles and have the horizontal part 9 secured beneath the rectangular upper wire-support 10. A lower wire support 11 is rectangular

in shape and has an arched part 12. Wire mesh 13 of any suitable character is secured to the upper and lower supports 10 and 11 to form a cage as shown in Figures 4, 5 and 6. The arched wire mesh 14 secured to the arched part extends in an arch shape to the opposite side of the cage and is secured thereto as indicated at 15 in Figure 6. The landing step 16 has cage 8 embedded therein and horizontal bolts 17, partly embedded therein, which extend through the wall 1 and have their ends spanned by a reinforcing plate 18. The ends are provided with nuts 19 for securing the bolts to the wall.

By constructing a stoop or stairway as above described one step will be locked to the other and the last step will hold the stoop or stairway in position by being secured to the wall as shown in Figure 1. The reinforcing cage strengthens the steps and prevents cracking. The arched under side of the step and the arched part of the cage make the steps light and rigid.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A stoop including concrete steps, the meeting corner of one step being provided with holes, the meeting corner of the other step being provided with a shoulder for receiving the corner of the first step, and vertical bars projecting from the shoulders and adapted to take into the holes of the first step.

2. A stoop including concrete steps provided with an arched part in the under side, the meeting corner of one step being provided with holes, the meeting corner of the other step being provided with a shoulder for receiving the corner of the first step, and vertical bars projecting from the shoulder and adapted to take into the holes of the first step.

3. A reinforcing frame for concrete steps including a rectangular upper wire support; a rectangular lower wire support having an

arched part; wire mesh secured to the upper and lower wire supports adapted to cover the supports and form a cage, and interlocking bars secured to the upper wire support and having one of their ends projecting upwardly.

4. The combination with a wall of a concrete landing step; bolts embedded in the step and having their ends extending

through the wall; a plate spanning the ends, and means for securing the bolts to the wall.

In testimony whereof I have signed my name to this specification in the presence of two subscribing witnesses.

HARRY A. DALY.
